UNITED STATES PATENT OFFICE.

JOHN HINES, OF LONDON, ENGLAND.

MEANS FOR MAKING OR REPAIRING ROADS AND LIKE SURFACES.

1,247,272.

Specification of Letters Patent. Patented Nov. 20, 1917.

Application filed December 23, 1916. Serial No. 138,541.

To all whom it may concern:

Be it known that I, JOHN HINES, subject of the King of Great Britain, residing at 289th Finchley road, London N.W., England, 5 engineer, have invented certain new and useful Improvements in Means for Making or Repairing Roads and like Surfaces, of which the following is a specification.

This invention comprises improvements 10 in the means for making, repairing, or improving roads and like surfaces. In the grouting or flush carpeting of roads with bituminous or other binding material to form a hard bound durable waterproof 15 road, work can only be satisfactorily carried out in fine dry warm weather, as the stone or other road making or dressing material must not only be quite free from moisture to insure good results but also 20 desirably heated to a given temperature, and as under normal conditions such material, after once being wet, takes a long time before it is rid of moisture, long delays occur entailing loss through cost of labor, 25 etc. It has been proposed with the object of avoiding these delays to dry and heat portions of road surface by forcing heated air on to the same beneath a hood so as to 30 prepare for the making or repairing operations.

The benefit of this method has not been obtained owing to the known apparatus necessitating uncovering the heated and dried road surface for the making or repairing 35 operations, and in this heated and dried state cold air and moisture present in the atmosphere are at once absorbed and the desired penetration of the binding material and filler is not obtained.

40 The object of my invention is to provide apparatus, embodying a suitable furnace or heater, and means for forcing or drawing air through same to a hood, with means for heating the binding materials and discharging 45 the same on to the road surface within the hood or immediately behind same, so that the absorbent properties of the heated and dried surface during cooling are utilized to effect the penetration of the grouting 50 of binding materials. Thus the added material marries with the existing road. The penetration of these materials is increased if they are discharged under pressure on to the road surface which is preferred.

Accordingly a portable apparatus is em-

ployed and the air heater or furnace is arranged with its outlet pipe or trunk passing through or alongside a container or containers for the bituminous or other binding material and preferably a container for the sand or other filling material, so as to heat the same as the hot air or gas forming a hot blast passes along the trunk to a hood or hoods directed over the road or like surface. 60 The heated bituminous material is led to sprayer pipes or nozzles beneath the hood and is forced into the heated and dried road surface within the hood. The sand or filler is preferably discharged into the trunk leading to the hood and a valve or deflecting plate is provided for shutting off or deflecting the hot air or gas from the hood into a sand receptacle upon the hood to blow the sand or other filler within the hood into 65 the road surface with the sprayed binding material. The blowing in of the sand or other filler by the current of hot air or gas is not an essential feature of the invention as the filler may be distributed in any other 70 way as by gravity. It is desirable that the current of hot air or gas should be cut off from the hood when the binding material is being distributed to avoid any risk of setting fire to the atomized or finely divided material. 75

On the drawings:—

Figure 1 is an elevation of a portable apparatus with my invention applied.

Fig. 2 is a plan thereof.

Fig. 3 is a rear end view of Fig. 1.

Fig. 4 is a longitudinal section of the apparatus shown at Fig. 1 omitting the front part of the chassis carrying the engine, blower, and associated mechanism.

Fig. 5 is a section of the hood.

These drawings show one example of construction in which I mount upon any suitable running frame *a*, a blower *b*, a suitable driving engine *c*, and a furnace or air heater *d*. The running frame may be adapted for propulsion or for trailing and any convenient arrangement for driving the blower or fan may be followed. Adjacent to the furnace or air heater is a tank *e* for the bitumen or like binding material with the main air or gas trunk *f* carried over or through the tank *e* and preferably along between that tank and a bin *g* for sand or like other finely divided filling material. The air or gas trunk *f* passes along to the rear end of the tank *e* where an outlet pipe *h* is pro-

vided leading to a hood *j* of conical or rectangular form. Preferably the hood is of square pyramidal form and the main enters at the vertex and preferably deflectors are arranged within the entrance to distribute the heated air or gas equally within the hood.

A by passage *k* for the air or gases may be arranged leading around the tank with 10 dampers *k*¹ in the main *f* so that the whole or part only of the gases may be sent around the tank. Any other arrangement of flues for circulating heat around the tank may be followed but preferably means will be provided in any case for insuring all the heat passing along the main trunk *f* when desired to the hood so as to insure sufficient for the purpose of drying and heating the road.

20 An important feature of the apparatus is the provision for spraying or distributing the binding agent tar, bitumen, asphalt, or other suitable binder, within the hood together with a heated filler such as sand, 25 chippings, clinker-dust, Portland cement, and the like, so that the binder and the filler are delivered or forced, preferably the latter, into the road surface within the hood which is within the zone of heat or immediately behind same. For this purpose a 30 pipe from the tank *e* leads to a spraying or distributing pipe *l* which may, if desired, be provided with spraying nozzles of any suitable construction. A pressure pump *m* 35 may be employed to force air above the bitumen, asphalt, tar, or any other binder within the tank *e* to force the heated liquid to the sprayers to insure its atomization or fine division and to facilitate its penetration into the road. Any other means of forcing the liquid may be employed.

For the "filler" feeding screws such as *n* Fig. 4 or any other conveying means, may be employed in the bin *g* and the filler may 45 be discharged into the outlet *h* and in the illustrated arrangement it enters a receptacle *o* on the hood *j* and is blown by the heated air or gas through the slot *p* into the hood near the liquid discharge.

50 A deflecting valve *q* is shown for closing the normal entrance to the hood so as to deflect the filler and the current of heated air or gas into the receptacle *o* see Fig. 5. The screws *n* in the sand bin *g* may be driven 55 from the road wheels or by hand or power as desired. The bottom of the receptacle *o* down which the sand, etc., will fall in its discharge may be curved transversely or provided with radiating ridges or grooves 60 or any like means for facilitating even distribution of finely divided materials may be employed. A deflector *o*¹ may be employed so that the filler may be discharged within or outside the hood as desired.

65 It is preferable to provide a cold air inlet

to the heated air of the trunk *f* for example as at *r* so that cold air may be admitted for regulating the temperature of the binder and "filler," or if desired a by pass direct from the fan or blower, suitably controlled, 70 may be employed but this is not claimed *per se*. It is desirable to provide flues or linings so that the heated air or gases may be utilized when desired entirely for heating the binding agent and the filler for example when the machine is not at work. 75

Beyond the hood *j* a second sprayer pipe *s* Fig. 2 may be carried by an extension *t* so that a second coat of the binder may be given to a treated surface as the hood is 80 drawn forward for further operation.

It will be understood that the invention is not limited to the above construction which is given as an example only.

I claim:—

1. In an apparatus for making and repairing roadways and like surfaces, the combination of a binder container, means for producing a hot-blast to heat the binder container, means for confining and directing the hot-blast upon an area of the roadway to heat and dry the same, means for protecting the heated and dried area from exposure to the surrounding atmosphere, and means for delivering material from within the binder container upon the said heated and dried area while in that condition.

2. In an apparatus for making and repairing roadways and like surfaces, the combination of a binder container, a filler container, means for producing a hot-blast to heat the binder container and the filler container, means for confining and directing the hot-blast upon an area of the roadway to heat and dry the same, means for protecting the heated and dried area from exposure to the surrounding atmosphere, and means for delivering materials from within the binder container and the filler container upon the said heated and dried area while in that condition.

3. In an apparatus for making and repairing roadways and like surfaces, the combination of a binder container, a filler container, means for producing a hot-blast to heat the binder container and the filler container, means for confining and directing the hot-blast upon an area of the roadway to heat and dry the same, means for protecting the heated and dried area from exposure to the surrounding atmosphere, and means for causing the hot-blast to deliver material from the filler container upon the heated and dried area while in that condition, and means for also delivering material from the binder container thereupon.

4. In an apparatus for making and repairing roadways and like surfaces, the combination of a binder container, means for producing a hot-blast to heat the binder con-

- tainer, means for confining and directing the hot-blast upon an area of the roadway to heat and dry the same, means for protecting the heated and dried area from exposure to the surrounding atmosphere, and means for delivering material from within the binder container upon the said heated and dried area while in that condition beneath the protecting means and also adjacent thereto.
5. In an apparatus for making and repairing road surfaces, the combination, with a carriage, of a heater, a blower to deliver a current of air through the heater to create a hot-blast, a binder container provided with discharging means, a filler container provided with rotary discharging means, flues from the heater contiguous to the exteriors of said containers, a surface protecting hood,
10. 5. In an apparatus for making and repairing road surfaces, the combination, with a carriage, of a heater, a blower to deliver a current of air through the heater to create a hot-blast, a binder container provided with discharging means, a filler container provided with rotary discharging means, flues from the heater contiguous to the exteriors of said containers, a surface protecting hood,
15. 5. In an apparatus for making and repairing road surfaces, the combination, with a carriage, of a heater, a blower to deliver a current of air through the heater to create a hot-blast, a binder container provided with discharging means, a filler container provided with rotary discharging means, flues from the heater contiguous to the exteriors of said containers, a surface protecting hood,
20. a flue for directing the hot-blast downward within the hood and conduits from the containers to points within the hood.
6. In an apparatus for making and repairing road surfaces, the combination, with a carriage, of a heater, a blower to deliver a current of air through the heater to create a hot-blast, a binder container provided with discharging means, a filler container provided with rotary discharging means, flues from the heater contiguous to the exteriors of said containers, a surface protecting hood,
25. a flue for directing the hot-blast downward within the hood and conduits from the containers to points within and without the hood.

In testimony whereof I affix my signature. 35
JOHN HINES.
